[57] CLAIM

The ornamental design for a police radar detector, as shown.

DESCRIPTION

FIG. 1 is a front elevational view of a police radar detector showing our new design;

FIG. 2 is a side elevational view of the detector shown in FIG. 1 and taken from the right to side thereof; FIG. 3 is a left side elevational view of the detector shown in FIG. 1;

FIG. 4 is a top plan view of the detector shown in FIG. 1;

FIG. 5 is a rear elevational view of the detector shown in FIG. 1; and

FIG. 6 is a bottom plan view of the detector shown in FIG. 1.

*Fig. 1.**Fig. 2.**Fig. 3.**Fig. 4.**Fig. 5.**Fig. 6.*
